DIPLEXING NETWORK

Oakley M. Woodward, Jr., Princeton, N. J., assignor to Radio Corporation of America, a corporation of Delaware

Application December 30, 1949, Serial No. 135,856

14 Claims. (Cl. 219—47)

1

This invention relates to radio frequency power networks wherein two independent sources, which must be electrically isolated from one another, are required to supply energy simultaneously to a common load device.

Diplexing networks, or networks for coupling two sources of radio frequency energy without interaction, to a common load, such as an antenna system, are known and find extensive application in the art. One such system is disclosed and claimed in Patent No. 2,454,907, issued to G. H. Brown on November 30, 1948, for "Radio Frequency Network." In an application filed October 4, 1948, for "Radio Transmitters," Serial No. 52,635, by G. H. Brown and assigned to a common assignee, there is described and claimed a coaxial line bridge circuit which is used as a diplexer.

The elements used in these types of diplexing networks are all on the order of half wavelengths or quarter wavelengths at the frequency of operation. At the higher frequencies, in view of the shorter wavelengths, these diplexing networks are of a convenient size and may be readily handled. But at frequencies on the order of 20-30 megacycles and lower, such diplexing networks become quite large and complex in view of the greater wavelengths. They consequently become awkward to handle and occupy valuable space.

It is therefore an object of my present invention to provide an improved diplexing network which is more compact than diplexers of the prior art.

It is another object of my present invention to provide an improved diplexing network which is simpler than diplexers of the prior art.

These and further objects of my invention are achieved by connecting two individual sources of radio frequency energy to a load composed of two substantially equal impedance loads connected together or a single load having a center tap. The connections are made by means of coiled transmission line elements which are bifilar wound and, or, trifilar wound. Connections are made so that the current applied by one of the generators is out of phase across the load and the current applied by the other generator is in phase across the load. The generator supplying the out-of-phase load current is placed at a point of zero potential with reference to the generator supplying the in phase currents by means of the multifilar windings connecting each generator to the load. The multifilar windings between the load and the generator supplying the in phase current acts as a radio frequency choke to any currents from the in phase current supply generator. Thus

2

both generators are effectively decoupled from one another. The term multifilar coil is used here to mean a coil having two or more windings which are wound so that there is no mutual inductance between the windings.

The novel features of the invention, as well as the invention itself, both as to its organization and method of operation, will best be understood from the following description, when read in connection with the accompanying drawings in which:

Figures 1 through 3 are schematic diagrams of three embodiments of my invention, and

Figure 4 is a sectional view of a pair of radio frequency electrodes illustrative of one type of load which may be used with the embodiments of my invention.

Referring to Figure 1, a radio frequency generator 10 generates a voltage E_a and is connected to a load 12 through a trifilar coil 14. The trifilar coil 14 is made to have an electrical length of one quarter wave length at the midband frequency of operation of generator 10. Two of the trifilar coil windings are connected to one side 11 of the generator 10. The third trifilar coil winding is connected to the other side of the generator. This side is shown as connected to ground. The load 12 may be a single load having three input terminals 16, 18, 20 with terminal 18 being a center tap terminal and the impedance of each half of the load being equal to R . The load 12 may also represent two equal unbalanced loads each of impedance R and each being joined to the other at one end at the terminal 18. The trifilar coil winding connected to the ground side of the generator 10 is connected at its other end to the terminal 18 and to ground. The remaining two trifilar coil windings are respectively connected to terminals 16 and 18, it being immaterial which of the two windings goes to terminal 16 or 18.

Another radio frequency generator 22 which generates a voltage E_b is connected to terminals 16 and 20 of the load by a bifilar coil 24. The bifilar coil 24 is made to have an electrical length of one quarter wave length at the midband frequency of operation of generator 20. One side of the generator 22 is grounded. The arrows in the diagram indicate the direction of flow, at the load 12, of currents I_a and I_b from respective generators 10 and 22. Energy from generator 10 is fed by the trifilar coil, acting as a three wire transmission line, to the load 12, so that the currents I_a at terminals 16 and 20 are in phase. For this condition the bifilar coil 24 acts as a high impedance choke coil to these in phase currents and

hence no current flows in generator 22 from generator 10. Thus generator 10 is isolated from generator 22.

The bifilar coil 24 serves the purpose, as in the prior art, to couple an unbalanced generator 22 to a balanced load 12. For this condition the current I_b from generator 22 is out of phase at terminals 16 and 20, and side 14 of generator 10 is at zero potential. Hence, generator 10 is decoupled from generator 22.

The trifilar coil 14 acts as a quarter wave stub (at midband frequency) with the winding connected to terminal 18 at ground potential. If the impedance of each of the load sections is R , the characteristic impedance of the bifilar coil 24, Z_b , should be made $\sqrt{2}R$ in order that the generator 22 see an impedance equal to R . In order that the generator 10 see an impedance R when looking toward the load the characteristic impedance Z_t of the trifilar coil is made equal to

$$\frac{R}{\sqrt{2}}$$

Figure 2 is a schematic diagram of a second embodiment of my invention using two trifilar coils. The arrangement of generator 10, trifilar coil 14 and load 12 is the same as is shown in Figure 1 and need not be redescribed. A trifilar coil 26 couples generator 22 to the load 12. Two of the trifilar coil windings are connected together at one end and then connected to terminal 18, the generator 22 is connected between the other end of these two windings. The third winding of the trifilar coil 26 is connected between terminal 20 and the grounded side of generator 22.

The effect of connecting trifilar coil 26 in the fashion described is to provide the same result as is achieved with bifilar coil 24. The current from generator 22 is out of phase at terminal 16 and 20 and accordingly generator 22 is decoupled from generator 10. Also trifilar coil 26 acts as a high impedance radio frequency choke to the currents from generator 10 and thus generators 10 and 22 are isolated. Trifilar coil 26 is made to have an electrical length of one quarter wave length at the midband frequency of generator 22. Its impedance is made equal to

$$\frac{R}{\sqrt{2}}$$

in order that generator 22 see an impedance equal to R .

Figure 3 is a schematic diagram of another embodiment of my invention using only bifilar coils. The interconnections of the load 12, the bifilar coil 24, and the generator 22 are as heretofore described. Generator 10 is connected to the load 12 by means of two bifilar coils 28, 30, each of which has an impedance equal to $\sqrt{2}R$ and an electrical length of one quarter wave length at the frequency of operation. The generator 10 is connected between the windings at one end of each of the bifilar coils 28, 30. The other ends of the windings of the bifilar coils 28, 30 which are connected to point 11 on the generator, are respectively connected to terminals 16 and 20 at the load. The remaining windings of the bifilar coils are connected to terminal 18 and grounded.

The connections of the bifilar coils 28, 30 effectively produce the same results as the trifilar winding 14 connections shown in Figures 1 and 2. In phase currents I_a are produced at terminals 16, 20. Point 11 is at zero potential with refer-

ence to the out of phase currents produced by generator 22 at terminals 16, 20 and therefore generator 22 is effectively decoupled from generator 10.

Any type of radio frequency load may be used as the load 12. A transmitting antenna array adjusted to be balanced and to provide three input terminals is a most common load for this type of diplexing network. A television picture transmitter and a sound transmitter may both be fed into a double line antenna, such as a turnstile antenna, without interaction between the two transmitters. Where resistance stabilization of an antenna array is desired, either of the generators, 10, 22 may be replaced by a reflection absorbing resistance. The diplexing system also may be used in a receiving system for isolating two receivers, substituted in place of the generators 10, 22 and fed by a common antenna. By substituting an absorbing resistor in place of one of the receivers, reflections caused by a mismatched antenna may be eliminated. The impedance values shown are the preferred ones. However these are not to be taken as limiting values since other impedance ratio values of load generators and multifilar coils may be used in accordance with good impedance matching practices and substantially the same results may be obtained as with the recommended impedance ratios.

In an application by George H. Brown for an "Improvement in Radio Frequency Heating System," filed September 1, 1949, No. 113,581, and assigned to a common assignee, it is shown that two generators may be used to feed a common pair of bar electrodes used in radio frequency heating. If one generator applies in phase voltages at the ends of one of the bar electrodes and the other generator applies out-of-phase voltages at the same ends of the same bar electrode, more uniform heating is obtained and more power along the bar electrode. Any of the embodiments of the present invention shown herein may be used to isolatingly couple two R. F. heating generators to a common pair of bar electrodes in accordance with the teachings of the application of Brown.

Figure 4 is a sectional view of an upper bar electrode 32 and a lower bar electrode 34, which 50 may be a bed plate, heating a dielectric load 36. Terminals 16 and 20 are approximately at the ends of the upper bar electrode 32. Terminal 18 may be the lower bar electrode 34. Connections may be made to the electrodes from the generator using the multifilar wound coils as above shown.

From the foregoing description, it will be readily apparent that I have provided an improved diplexing system, which, in view of the coiled elements used, is more compact and simpler than systems of the prior art. Although I have shown and described several embodiments of my invention, it should be apparent that many other embodiments are possible, all within the spirit and scope of my invention. Therefore, I desire that the foregoing description shall be taken as illustrative and not as limiting.

What is claimed is:

1. A system for excitation from two sources of radio frequency energy without interaction comprising a load having three input terminals, one of which is a center tap terminal for said load, at least one multifilar winding connected between one of said radio frequency energy sources and said three input terminals and another multi-

5
filar winding connected between the other of said radio frequency energy sources and two of said input terminals exclusive of said center tap terminal, each of said multifilar windings being one quarter wavelength at the midband frequency of the radio frequency energy source to which it is connected.

2. The system recited in claim 1 where at least one multifilar winding is a trifilar winding and said other multifilar winding is a bifilar winding.

3. The system recited in claim 1 where at least one multifilar winding is a trifilar winding and said other multifilar winding is a trifilar winding.

4. The system recited in claim 1 where at least one multifilar winding consists of a pair of bifilar windings and said other multifilar winding is a bifilar winding.

5. The system recited in claim 1 wherein said load comprises a pair of bar electrodes for radio frequency heating, one of said bar electrodes having said center tap terminal connected to it, the remaining two input terminals being positioned on each end of the other bar electrode.

6. An isolation network for radio frequency power systems including a pair of radio frequency loads each having a first and second input terminal, said second input terminals being connected together, a bifilar winding one quarter wavelength long at the operating frequency, one end of said bifilar winding serving as a radio frequency power input and each winding at the other end being respectively connected to said first input terminal of each load, and a trifilar winding one quarter wavelength long at the operating frequency, one end of said trifilar winding serving as a radio frequency power input and each winding at the other end being respectively connected to each of said first terminals of said pair of loads and to said second terminals.

7. The system recited in claim 6 wherein the impedance of said bifilar coil is determined as

$$Zb = \sqrt{2R}$$

and the impedance of the trifilar coil is determined as

$$Zt = \frac{R}{\sqrt{2}}$$

where

Zb is the impedance of the bifilar coil and Zt is the impedance of the trifilar coil and R is the impedance of one of said loads.

8. An isolation network for radio frequency power systems including a pair of radio frequency loads each having a first and a second input terminal, said second input terminals being connected together, first trifilar coil one quarter wavelength long at the desired operating frequency, having one end as a radio frequency power input, and having each winding at the other end connected respectively to a first terminal of one of said loads, to a first terminal of the other of said loads, and to the connected second terminals, and a second trifilar coil one quarter wavelength long at the desired operating frequency, having one end as a radio frequency power input, having two of said windings at the other end connected to said first terminal of one of said loads and having the third of said second trifilar coil windings at the other end connected to said first terminal of the other of said loads.

9. The system recited in claim 8 wherein the

6
impedance of said first and second trifilar coils is determined as

$$Zt = \frac{R}{\sqrt{2}}$$

where

Zt is the impedance of the trifilar coil, and R is the impedance of one of said loads.

10. An isolation network for radio frequency power systems including a pair of radio frequency loads each having a first and second input terminal, said second input terminals being connected together, a pair of bifilar coils, each one quarter wavelength long at the operating frequency, one winding in each of said pair of bifilar coils being connected together at one end and to said second input terminals, the other winding of each of said pair of bifilar coils being respectively connected at said one end to each of said first input terminals, the other ends of said one of said pair of bifilar coils being connected to the other end of said other of said pair of bifilar coils to serve as a radio frequency power input terminal, and a third bifilar coil having each winding at one end being respectively connected to each of said first terminals, the other end of said third bifilar coil serving as a radio frequency power input terminal.

11. The system recited in claim 10 wherein the impedance of each of one of said pair of bifilar coils and said third bifilar coil is determined as

$$Zb = \sqrt{2R}$$

where

Zb is the impedance of said bifilar coil, and R is the impedance of one of said loads.

12. A system for excitation from two sources of radio frequency energy without interaction comprising a radio frequency load having first second and third input terminals, said second input terminal being said load center tap terminal, a trifilar coil one quarter wavelength long at the operating frequency, each of the windings at one end of said trifilar coil being connected to a respective one of said input terminals, one of said sources of radio frequency energy being connected to the other end of said trifilar coil between the winding connected to said second terminal and the windings connected to said first and third terminals, and a bifilar coil one quarter wavelength long at the operating frequency, said bifilar coil having the windings at one end connected to said first and third terminals and the other of said sources of radio frequency energy connected between the windings at said other end.

13. A system for excitation from two sources of radio frequency energy without interaction comprising a radio frequency load having first, second and third input terminals, said second input terminal being said load center tap terminal, a first trifilar coil one quarter wavelength long at the operating frequency, each of the windings at one end of said trifilar coil being connected to one of said input terminals, one of said sources of radio frequency energy being connected to the other end of said trifilar coil between the winding connected to said second input terminal and the other two windings, and a second trifilar coil one quarter wavelength long at the frequency of operation, said second trifilar winding having at one end two of its windings connected to said first terminal and its third winding connected to said

third terminal, the other of said sources of radio-frequency energy being connected to the other end of said second trifilar coil between one of said windings connected to said first terminal and the other two of said windings.

14. A system for excitation from two sources of radio frequency energy without interaction comprising a radio frequency load having first, second and third input terminals, said second input terminal being said load center tap terminal, a first bifilar coil one quarter wavelength long at the operating frequency, one end of said bifilar coil being connected to said first and third terminals, one of said radio frequency sources being connected between the other end of said first bifilar coil, and a pair of bifilar coils each being one quarter wavelength long at the frequency of operation, the windings at one end of one of said pair of bifilar coils being connected

5 to said first and second terminals, the windings at one end of the other of said pair of bifilar coils being connected to said second and third terminals, said other radio frequency energy source being connected to the other ends of said pair of bifilar coils between the windings connected to

10 said first and third terminals and the windings connected to said second terminal.
